UNITED STATES PATENT OFFICE.

I. C. EMERY, OF BALTIMORE, MARYLAND, ASSIGNOR TO CHAPMAN SELF LOCKING NUT COMPANY, OF BALTIMORE, MARYLAND, TRUSTEES OF A COMMON-LAW TRUST ESTATE.

APPARATUS FOR MAKING LOCK-NUT BLANKS.

Application filed October 8, 1925. Serial No. 61,255.

This invention relates to an apparatus for making lock nut blanks and has for its object to improve the means heretofore proposed.

- 5 With this and other objects in view the invention consists in the novel steps and combination of steps constituting the process and in the novel parts and combinations of parts constituting the apparatus all as will be more 10 fully hereinafter disclosed and particularly pointed out in the claims.

Referring to the accompanying drawings forming a part of this specification in which like numerals designate like parts in all the 15 views:

Fig. 1 is a side elevational view partially broken away of a machine made in accordance with this invention;

20 Fig. 2 is a sectional view taken on the line 2—2 of Fig. 1, looking in the direction of the arrows;

Fig. 3 is an end elevational view of a portion of the parts shown in Fig. 1;

25 Fig. 4 is a sectional view taken on the line 4—4 of Fig. 2, looking in the direction of the arrows;

Fig. 5 is a sectional view taken on the line 5—5 of Fig. 1, looking in the direction of the arrows;

30 Fig. 6 is a sectional view taken on the line 6—6 of Fig. 3, looking in the direction of the arrows;

Fig. 7 is a detail partially sectional view showing one position of the parts before the 35 partially formed blank is pushed from its forming die onto its swaging die;

Fig. 8 is an elevational and partially sectional view of a portion of the parts shown in Fig. 7 illustrating the down position of the 40 forming punch and its associated parts;

Fig. 9 is a detail view showing the forming punch of Figs. 7 and 8 in its raised position;

Fig. 10 is a view of the parts shown in Fig. 7 after the plunger member has moved the 45 partly formed blank into its swaging position;

Fig. 11 is a sectional view taken on the line 11—11 of Fig. 10 showing the blank ready to be flattened or swaged;

50 Fig. 12 is a sectional view of the parts shown in Fig. 11 after the swaging action has taken place;

Fig. 13 is an enlarged detail sectional view of a portion of the parts shown in Fig. 12;

Fig. 14 is a perspective view of the finished 55 nut blank before it has been perforated and threaded;

Fig. 15 is a perspective view of a drop forging or casting forming a base member of the 60 machine;

Fig. 16 is a sectional view of the forming portion of a somewhat modified form of machine especially adapted for making large 65 sized nut blanks;

Fig. 17 is a sectional view taken on the 70 line 17—17 of Fig. 16, looking in the direction of the arrows;

Fig. 18 is a sectional view taken on the line 18—18 of Fig. 17, looking in the direction of the arrows;

Fig. 19 is a sectional view illustrating the 75 position of the parts after the blank has been moved over to the knife edge former and subjected to a swaging action;

Fig. 20 is a sectional view taken on the 80 line 20—20 of Fig. 19, looking in the direction of the arrows;

Fig. 21 is a detailed sectional view of a portion of the parts associated with the swaging die;

Fig. 22 is a detailed sectional view of the 85 parts shown in Fig. 21 when the said parts are in a different position of operation;

Fig. 23 is a perspective view of the split 90 slide employed in this modified form of the invention;

Fig. 24 is a perspective view and a side elevational view of the large size nut blank made on this modified form of machine;

Fig. 25 is a view similar to Fig. 24 showing 95 the condition of the nut blank that would prevail were the machine not provided with the split slide shown in Fig. 23.

Referring first to Fig. 15, 1 represents a drop forging or casting forming a base member of this machine which is of the shape shown. That is to say, this base member 1 is provided with the end members 2 and 3 separated by the vertically disposed hollow spaces 4 and 5, and said end members 2 and 3 are joined by the connecting member 6. Said member 2 is larger than is the member 3 and is provided at one side with the cut-out groove or channel 7, and on its top surface

with the widened groove or channel 8 forming a slide way. Said member 3 is provided with the slide way 9 which is somewhat similar to the slideway 8. The member 2 is provided with a vertically disposed rectangular passage, channel or well 10, and the member 3 is provided with the similar well 11. As will be clear from the other figures, and especially Figures 11 and 12 there reciprocates in the well 10 the cam shaped plunger 13, and there reciprocates in the well 11 the cam shaped plunger 14. The said plungers 13 and 14 are connected by any suitable member or cross head such as 15 as will likewise be clear from Figs. 1, 2, 11 and 12. The member 2 is provided on its end surface with a plate member 16 which is secured to said member 2 as by the bolts 17, and said member 2 is also provided with a cover plate made in two halves and lettered 18 and 19 through which the plunger member 13 passes. A second cover plate 30 extends above the end member 3 through which the plunger member 14 passes, as best shown in Figs. 11 and 12. It will further be observed from the above mentioned figures that between the cover plates 18 and 19 and the top surface of the member 2 there is disposed the compressing slide or swaging member 20, and between the cover plate 30 and the top surface of the member 3 there is disposed the swaging slide or member 21. In the recess 7 of the portion 2, Fig. 13, there is placed the hardened steel member 22, see Figs. 1 and 2, and this member has its top surface 23 flush with the top surface 24 of the member 2, so that its upper edge 25, Fig. 4, constitutes a cutting edge. A portion of the cover plate is cut away to form the passage 26 through which the stock 27 to be formed into nut blanks may be fed as will be clear from Figs. 1 and 4.

Into the space 4, see Fig. 15, there is dropped or wedged the block 31, see Fig. 4, which block is provided with the hardened flat steel blade, or forming die 32, held in place by the pin 33, and whose tapered end 34 stops just below the stock material 27 as shown. In close proximity to the block 31 and resting upon the surface 35, Fig. 15, is placed the hardened steel block 36, Fig. 12, which carries the hardened steel knife blade or separator 37 secured to the block 36 as by the pin 38 illustrated in Figs. 7, 10 and 11. The block 36 thus rests upon the surface 35 and fits up snugly against the wall or partition 39 joining the two members 2 and 3 as best shown in Fig. 15.

Also carried by the cross head 15 and moving therewith are a forming and cutting plunger or punch 40, and a swaging plunger or punch 41. The punch 40 is provided with the cutting edge 43 which descends and strikes the stock strip at the point 44, Fig. 3, and shears it off against the cutting edge 25,

Figs. 3 and 4. As said punch 40 continues to descend its cut away or hollowed out portion 46 straddles the forming die 32 and bends the cut off stock down on both sides of the tapered end portion 34, thus forming the blank 47 into the V-shape shown in Figs. 8 and 9.

The stock strip 27 is fed to its position beneath the plunger or punch 40 by hand or by any suitable means not shown, and its extreme end edge contacts with the plate 30 which forms a stop for the feeding motion when the right length of the strip is beneath the punch 40 all as will be clear from Fig. 4.

As the plunger 40 rises from the forming position shown in Fig. 8 to the position shown in Fig. 3, the partly formed blank 47 is liable to find itself wedged into the space 46 of said plunger 40, and to rise with it. To prevent this there is provided the ejector pin 50, which is adapted to reciprocate in a bore of said plunger 40. That is, said pin 50 is provided with an enlarged or shouldered portion 51 which permits said pin to descend to such a distance that only its extreme end 52 can descend a short distance below the top of the space 46 and thus eject the blank 47 after the forming action is had. Said pin 50 and head 51 is controlled by the member 54, controlled in turn by the spring 55 whose compression is governed by the screw 56. It thus results that when the plunger 40 descends the spring 55 is compressed due to the members 50 and 54 rising into the positions shown in Fig. 8 and when the plunger 40 begins to ascend the said spring 55 expands thus forcing the end 52 of the pin 50 into the position shown in Fig. 9, and at the same time expelling the partly formed blank 47 out of the space 46, whereupon said blank falls back upon the tapered end 34 of the blade or die 32.

After the blank 47 has thus been replaced upon the top of the die 32, the parts are so timed that the longitudinally disposed finger 60 moves toward the right as seen in Fig. 6 and pushes said blank off of the tapered end 34 of the die 32 and onto the thin blade like separator 37. It should be stated that as will be clear from Fig. 1, the power actuated member 61 of the machine is reciprocated up and down by means, not shown, and said motions in turn move up the pitman member 62 controlled in its down movement by the spring 63, and that this said member 62 in turn being pivoted as at 64 to the bell crank 65, which in turn is pivoted as at 66 to the machine, reciprocates through the slot 67 and pin 68 the said horizontally disposed member 60 all as will be clear from Figs. 1 and 6 of the drawings. The extreme end of said member 60, however, is provided with the hollow member 70 which is U-shaped in cross section and thus straddles the die member 32 as will be clear from Fig. 6 to facilitate the movement of the par-

tially formed blank 47 from the extreme upper end 34 of said die member to the knife blade separator 37.

The partially formed blank 47 being thus brought into position on the separator 37 beneath the swaging punch 41, said punch descends along with the plunger member 40 and with the cross head 15, down upon said partially formed blank 47, immediately after the 10 swaging or compressing members 20 and 21 have compressed the said blank 47 into the shape shown in Fig. 12. That is to say, as the cross head 15 descends it carries down with it not only the plungers 40 and 41 but 15 also the cam members 13 and 14 provided with the cams 71 and 72 respectively which coact with the corresponding cams 73 and 74 respectively to move said die members 20 and 21 from the positions shown in Fig. 11, to 20 the positions shown in Fig. 12. Immediately after this compressing action upon the nut blank 47 is had, the swaging punch 41 descends as best shown in Figs. 12 and 13 and suitably shapes the nut blank 47 into the form 25 illustrated in Fig. 14. Upon the rising of the cross head 15 the members 13 and 14 rise from the positions shown in Fig. 12 to the positions shown in Fig. 11, whereupon the cam members 75 and 76 take against the cam surfaces 77 and 78 respectively of the compressing members 20 and 21 and return said members from the positions shown in Fig. 12 to the positions shown in Fig. 11. The parts are 30 now ready for another portion of the stock 35 material 27 to be cut off by the edge 43 of the plunger 40 and to be partially formed into the V-shape shown in Figs. 9 and 11, and are in position for said partially formed blank 47 to be pushed toward the right as seen in Fig. 7 by the member 70 of the reciprocating plunger 60. As we now have the completed nut blank 80 shown in Fig. 14 resting upon the separator 37, the movement of this second V-shaped partially formed blank 47 toward the right as seen in Figs. 7 and 10 will 45 cause said completely formed nut blank 80 to be pushed toward the right off of the separator 37; and this latter finished blank 80 will thus slide down the incline 81, see Fig. 6, and 50 through the space 5, see Fig. 15, into a suitable receptacle not shown.

In the somewhat modified form of the invention shown in Figs. 16 to 25 inclusive, a defect which appears in the finished blanks 55 80 made on the preceding mechanism is cured. That is to say, it has been found that when blanks of a moderately large size are formed in the manner just disclosed the upper edges 60 of the crown portions 84 are bulged out as indicated at 85 in Figs. 25 while small sized nut blanks do not show this defect. That is to say, when the swaging plunger 41 descends as indicated onto the larger sizes of nut blanks the metal flows laterally as indicated at 85 in Fig. 25, thus requiring another operation to

remove these projections and it is the purpose of this modified form of construction to do away with this objection.

Referring more particularly to the above mentioned Figures 16 to 25, the same parts are lettered with the same numerals as in the preceding figures and the operation of said parts are the same as in the preceding figures. But the slide horizontally disposed compressing plates or members 20 and 21 in the preceding figures are greatly narrowed in this modified form of invention and are lettered 70 90 and 91 respectively. This narrowing of the plates 90 and 91 leaves a considerable space or channel on each side of the said plates 75 in which reciprocates the split slide member 92 all as will be clear from Figs. 20 and 21. Said split slide member is provided with the side members 93 and 94 which are separated by the space 95 and which reciprocate on each 80 side of the slides 90 and 91, and said side members 93 and 94 are provided with the cut away portions or rectangular openings 96 and 97 respectively, as best shown in Fig. 21. The said split slide member 92 is also provided with the pin or other connection 98 to which is attached the fork like members 99 rigid with the oscillating member 100 mounted on the shaft 101 which is rocked by any suitable means such for example as the 95 arm 110 provided with the fork 111 that may be connected to the pitman member 62 all as will be clear from Figs. 1 and 17. It thus results that the parts being properly timed and proportioned, and in the position shown in 100 Figs. 19 and 20, the side members 93 and 94 straddle the partly finished blank 47 when it is resting upon the knife blade or separator 37, and they hug so tightly the wings 102 of the enlarged blank 103 illustrated in Fig. 24, 105 that said wings 102 including the top crown portion 104 cannot under the swaging action bulge out as indicated at 85 in Fig. 25 or when compression is applied to said nut blank 103 as best indicated in Figs. 19 and 20. The result is a finished nut blank of large size, such as is shown in Fig. 24, that is smooth at the point 104; and, therefore, it needs no second 110 operation to finish the same ready for perforating and threading. On the other hand, 115 the parts are likewise so timed and proportioned that when the partly finished blank 47 rests upon the upper tapered end 34 of the forming die 32, as best illustrated in Fig. 16, the openings 96 and 97 of the split slide member 92 register with said blank 47, and thus enable a pusher member 60 illustrated in Fig. 6, to push over the partly finished blank 47 from the die member 32 onto the knife blade separator 37 as disclosed above, whereupon 120 the plunger 41 after the parts have been compressed by the members 90 and 91 comes down onto the crown portion 84 of said blank and swages the same into shape, all as will be 125 understood from the preceding description 130

and Figs. 16 to 20 of the drawings. After the plunger 41 in connection with the compressing members 90 and 91 has thus completed the nut blank 103, the next blank that is shovved off the tapered edge 34 of the die 32 onto the separator 37 will push the finished blank 103 off of said separator 37, whereupon it will pass through the opening 96 of the member 92 and fall down through the opening 106 which is or may be substantially the same as the opening 5 in Fig. 15, and into a receptacle not shown.

It will now be clear that by constructing a machine in the manner above disclosed and providing the drop forging or casting 1 made from a single piece of metal, one is enabled to greatly simplify the machine and to omit many moving parts that would otherwise have to be provided. It will also be apparent that by providing the split slide member 92 one is enabled to so confine the metal being swaged as to prevent an undesirable flow of the metal when large sized nut blanks are being made and to thus avoid a second finishing operation. It will also be apparent that this swaging action whether the member 92 is or is not used provides a nut blank having the bent over straight wings 102 united by the crown portion 84 in which the density of the metal will be increased due to the heavy compression to which it is subjected. It will further be clear that the finished blank is perforated as indicated by the dotted line circle 114 and later threaded by means not shown. Due to the employment of the casting or forging 1, the block 31 carrying the blank bending or folding die or post 32 may be readily attached to and detached from the said member 1, for it is only necessary to wedge said block into the space 6, Fig. 15, where it is to be used and to drive or otherwise force it out of said space when it is to be taken out for repairs or for other purposes. Substantially the same remarks apply to the block 36 and separator 37 both of which are readily wedged into position in the space 35, Fig. 15, and forced out of position for repairs, or for other purposes when the block 31 has been removed. All the removable parts may thus be made of hardened steel and readily replaced when worn out.

What is claimed is:

1. In a machine for making lock nut blanks the combination of a base member provided with two end portions separated by a vertically disposed recess and provided with a smaller recess; a block disposed in said smaller recess; a swaging die carried by said block; a block disposed in said first named recess; a folding die carried by said last named block; means carried by said base member to hold and to facilitate the feeding of a strip of metal to be cut; a plunger located above said base member provided with a cutting means and with a folding means

adapted to cut said metal and fold the same over said folding die; a swaging plunger also disposed above said base member adapted to swage any metal placed above said first named swaging die; and means to reciprocate said folding and swaging plungers.

2. In a machine for making lock nut blanks the combination of a base member provided with two end portions; folding and swaging dies carried by said base member; blank compressing means also carried by said end portions; folding and swaging plungers disposed above said base member adapted to fold and swage blanks disposed on said first named folding and swaging dies; and means to reciprocate said folding and swaging plungers toward and from said first named folding and swaging dies.

3. In a machine for making lock nut blanks the combination of a base member provided with two end portions separated by a vertically disposed recess and provided with a smaller recess; a readily attachable and detachable block disposed in said smaller recess; a separator carried by said block; a readily attachable and detachable block disposed in said first named recess; a folding die carried by said last named block; means comprising a recessed cover member carried by said base member to hold and to facilitate the feeding of a strip of metal to be cut; a cutting member carried by said base member; a plunger located above said base member provided with a cutting means adapted to coact with said first named cutting member and with a folding means adapted to fold the same over said folding die; a swaging plunger also disposed above said base member adapted to swage any metal placed above said separator; and means to reciprocate said folding and swaging plungers.

4. In a machine for making lock nut blanks the combination of a base member provided with two end portions having horizontally disposed recesses; folding and swaging dies carried by said base member; blank compressing means also carried by said end portions and disposed in said recesses; folding and swaging plungers disposed above said base member adapted to fold and swage blanks disposed on said first named folding and swaging dies; means to reciprocate said blank compressing means; and means to reciprocate said folding and swaging plungers toward and from said first named folding and swaging dies.

5. In a machine for making lock nut blanks the combination of a base member provided with two end portions; folding and swaging dies carried by said base member; horizontally disposed compressing members carried by said end portions; cam members coacting with said compressing members to reciprocate the same in said base member; reciprocating folding and swaging plungers coact-

ing with said first named folding and swaging dies; means to reciprocate said cam members and said folding and swaging plungers; means comprising a reciprocating member to transfer a partially folded blank from said first named folding die to said first named swaging die; and means comprising a bell crank connected to said last named means.

6. In a machine for making lock nut blanks from metal strips, the combination of a base member provided with two end portions separated on one side by a pair of vertically disposed recesses and provided with a pair of horizontally disposed recesses; said base member also provided in each end portion with a well passing from said last named recesses down into each end portion; readily attachable and detachable folding and swaging dies located in said vertically disposed recesses; reciprocating compressing dies located in said horizontally disposed recesses; a cutting means carried by said base member; a pair of reciprocating members provided with cam surfaces movable up and down in said wells; folding and swaging plungers coacting with said first named folding and swaging dies; and a reciprocating cutting means coacting with said first named cutting means.

30 7. In a machine for making lock nut blanks from metal strips, the combination of a base member provided with two end portions separated on one side by a pair of vertically disposed recesses and provided with a pair of horizontally disposed recesses; said base member also provided in each end portion with a well passing from said last named recesses down into each end portion; readily attachable and detachable folding and swaging dies located in said vertically disposed recesses; a reciprocating means provided with an end portion U-shaped in cross section for transferring a partially formed blank from said folding die to said swaging die; reciprocating compressing dies located in said horizontally disposed recesses; a readily attachable and detachable cutting means carried by said base member; a pair of reciprocating members provided with cam surfaces movable up and down in said wells; folding and swaging plungers coacting with said first named folding and swaging dies; and a reciprocating cutting means carried by said folding plunger coacting with said first named cutting means.

8. In a machine for making lock nut blanks having a base member made from a single piece of metal, provided with two end portions separated by vertically disposed recesses and also provided with horizontally disposed recesses in said end portions in combination with cutting means, a die folding means, and die swaging means located in said recesses.

65 9. In a machine for making lock nut blanks

having a base member made from a single piece of metal, provided with two end portions separated by vertically disposed recesses and also provided with horizontally disposed recesses in said end portions in combination with cutting means, a die folding means, and die swaging means located in said recesses; and with reciprocating folding, swaging, and blank transferring means located outside said recesses.

10. In a machine for making lock nut blanks the combination of a base member provided with two end portions having horizontally disposed recesses; folding and swaging dies carried by said base member; blank compressing means also carried by said end portions and disposed in said recesses; means located in said recesses to prevent the metal from spreading when subjected to a compressing action; folding and swaging plungers disposed above said base member adapted to fold and swage blanks disposed on said first named folding and swaging dies; means to reciprocate said blank compressing means; and means to reciprocate said folding and swaging plungers.

11. In a machine for making lock nut blanks the combination of a base member; folding and swaging dies carried by said base member; blank compressing means also carried by said base member; reciprocating means adapted to confine and prevent the flow of metal from the edge portions of the blank being operated upon also carried by said base member; reciprocating folding and swaging plungers disposed above said base member adapted to fold and swage blanks disposed on said first named folding and swaging dies; means to reciprocate said compressing means; and means to reciprocate said folding and swaging plungers toward and from said first named folding and swaging dies.

12. In a machine for making lock nut blanks the combination of a base member provided with two end portions having horizontally disposed recesses; stationary folding and swaging dies carried by said base member; horizontally disposed, reciprocating blank compressing means also carried by said end portions and disposed in said recesses; means located in said recesses on each side of said compressing means adapted to prevent the metal from spreading when subjected to a compressing action; folding and swaging plungers disposed above said base member adapted to fold and swage blanks disposed on said first named folding and swaging dies; means to reciprocate said blank compressing means; and means to reciprocate said folding and swaging plungers.

13. In a machine for making lock nut blanks the combination of a base member provided with two end portions having horizontally disposed recesses; folding and swaging dies carried by said base member; blank

- compressing means also carried by said end portions and disposed in said recesses; means located in said recesses to prevent the metal from spreading when subjected to a compressing action comprising a reciprocating sliding member provided with members disposed on each side of said compressing means, folding and swaging plungers disposed above said base member adapted to fold and swage 10 blanks disposed on said first named folding and swaging dies; means to reciprocate said blank compressing means; and means to reciprocate said folding and swaging plungers.
14. In a machine for making folded lock 15 nut blanks the combination of a blank folding means; a blank swaging means; and a movable means adapted to confine the edges of the blank and prevent the metal from spreading during the swaging operation, said 20 means so formed as to permit the blank being passed thereinto from the folding means.
15. In a machine for making folded lock nut blanks the combination of a blank folding means; a blank swaging means; and a movable 25 means comprising a reciprocating slide member adapted to confine the edges of the blank and prevent the metal from spreading during the swaging operation, said member provided with an opening in one of its sides 30 through which the blank is passed from the folding means.
16. In a machine for making folded lock nut blanks the combination of means to fold and swage said blanks into the desired shape; 35 and a reciprocating member coacting with
- said means adapted to contact with and confine the edges of said blank during the swaging operation and prevent the metal from spreading, said member provided with apertures through which the blank is received and 40 discharged.
17. In a machine for making folded lock nut blanks the combination of means to fold and swage said blanks into the desired shape; a reciprocating member coacting with said 45 means provided with a cut away portion and adapted to contact with and confine the edges of said blank during the swaging operation and prevent the metal from spreading; and means to discharge the finished blank through 50 said cut away portion.
18. In a machine for making folded lock nut blanks the combination of means to fold and swage said blanks; movable means provided with a cut away portion and coacting 55 with said swaging means to prevent the metal from spreading during the swaging operation; and means to move the finished blank through said cut away portion.
19. In a machine for making folded lock 60 nut blanks the combination of means to fold and swage said blanks; movable means comprising a split slide member provided with a cut away portion and coacting with said 65 swaging means to prevent the metal from spreading during the swaging operation; and reciprocating means to move the finished blank through said cut away portion.

In testimony whereof I affix my signature.

I. C. EMERY.
